UNITED STATES PATENT OFFICE.

JOHANN G. WILHELM PAUL, OF SCHILTIGHEIM, AND JOSEPH THAU, OF STRASSBURG, GERMANY.

FIREPLACE.

No. 833,414.

Specification of Letters Patent.

Patented Oct. 16, 1906.

Application filed November 20, 1905. Serial No. 288,258.

To all whom it may concern:

Be it known that we, JOHANN GEORG WILHELM PAUL, residing at No. 1 Schlittweg, in Schiltigheim, and JOSEPH THAU, residing at 5 No. 9 Marktgasse, in Strassburg, in the Imperial Province of Alsace-Lorraine, German Empire, subjects of the King of Prussia, German Emperor, have invented a certain new and useful Improvement in Fireplaces, of 10 which the following is a specification.

Our invention relates to that class of fireplaces in which air is introduced into the combustion-spaces above the bed of fuel by means of hollow blocks, the tapering air-passage of which serves to conduct air to the combustion-space.

The object of our invention is to provide means for preventing said hollow blocks from being overheated if one of the air-passages should be choked. To accomplish this object, we employ hollow blocks which are provided in one wall with a recess and in the opposite wall with a corresponding projection or nipple communicating with the interior of 20 the hollow blocks and adapted to engage one another when the blocks are set side by side, and thus forming a communication between all the blocks.

Referring to the drawings, Figure 1 shows 30 in section a hollow block such as we employ according to the present invention. Fig. 2 represents the same block in side elevation. Fig. 3 shows two blocks set side by side on a support, the nipple of the one engaging the recess of the other. Fig. 4 shows the blocks applied to the furnace of a boiler, the respective parts of the same being shown in longitudinal section. Fig. 5 is a transverse vertical section on the line 6 7 of Fig. 4.

40 By reference to Figs. 1 and 2 it will be seen that the hollow block *a*, the interior *f* of which is tapered from inlet to outlet and curved at the upper end, is provided with a shoulder and downward projections to rest 45 on a suitable support *g*. In one of the side walls of this hollow block there is an opening *d* and in the opposite wall a nipple or projec-

tion *c*, the passage *b* of which discharges into the interior of the hollow block. When setting these blocks side by side, as shown in 50 Fig. 3, the nipple *c* engages the recesses *d*, thus forming a continued communication throughout the series of blocks. Therefore if any of the air-passages of these blocks should be choked from beneath, so that air 55 would stagnate in these blocks, the circulation of air is maintained, owing to the communication with the air-passage of the neighboring block, and a destructive overheating of the blocks may not happen.

As shown in Figs. 4 and 5, the hollow blocks in question may be employed, for instance, in connection with the furnaces of boilers, as Galloway or Lancashire boilers. The blocks *a* in this case may be arranged in 60 two series at both sides of the grate *e*. The hot air passing from below through the grate also passes partially through the air-passages of the said blocks, mixing above the grate with the fire-gases and causing thus a complete combustion of the unburned portions of the same.

Having now described our invention, what we claim as new is—

In a stove or furnace, the combination of a 75 combustion-chamber, a fuel-support situated therein, and a plurality of air-supply blocks, arranged to form the walls of the combustion-chamber on opposite sides thereof, each of 80 said blocks consisting of an upright body having a vertical air-passage inwardly curved and contracted at its upper end, a lateral hollow projection on one side thereof communicating with said air-passage and a corresponding lateral aperture located in the opposite side thereof.

85 In witness whereof we have hereunto set our hands in presence of two witnesses.

J. G. WILHELM PAUL.
JOSEPH THAU.
